United States Patent

Des. 237,739
Patented Nov. 18, 1975

237,739

TELEVISION RECEIVER

Kenichi Itoh, Kawanishi, Tadahiko Tokuda, Osaka, and
Kazuhiko Ueda, Takatsuki, Japan, assignors to Matsu-
shita Electric Industrial Company, Ltd., Osaka, Japan

Filed Sept. 7, 1973, Ser. No. 396,274

Term of patent 14 years

Int. Cl. D14—03

U.S. Cl. D56—4 D

FIG. 1

FIG. 2

FIG. 3

FIG. 4

FIG. 5

FIG. 1 is a front, top and right side perspective view of a television receiver showing our new design;

FIG. 2 is a top plan view;

FIG. 3 is a left side elevational view;

FIG. 4 is a rear elevational view; and

FIG. 5 is a bottom plan view.

Portions of the figures are shaded to indicate contrast in appearance and portions are diagonally lined to indicate transparency.

We claim:

The ornamental design for a television receiver, as shown and described.
